UNITED STATES PATENT OFFICE

91,180

DESIGN FOR AN ELECTRIC TOASTER

Abe O. Samuels, Rochester, N. Y., assignor to
Samson-United Corporation, Rochester, N. Y.

Application September 27, 1933. Serial No. 49,361

Term of patent 7 years

To all whom it may concern:

Be it known that I, ABE O. SAMUELS, a citizen of the United States, residing at Rochester, in the county of Monroe and State of New York, have invented a new, original, and ornamental Design for an Electric Toaster, of which the following is a specification, reference being had to the accompanying drawing, forming a part thereof.

Figure 1 is a front elevation of the electric toaster showing my new design.

Figure 2 is an end elevation of the same.

Figure 3 is a top plan view of the same.

I claim:

The ornamental design for an electric toaster, as shown.

ABE O. SAMUELS.
